Chas. C. Gill

UNITED STATES PATENT OFFICE.

HARRY HAUPT, OF ELMSFORD, NEW YORK, ASSIGNOR TO KIMPTON, HAUPT & CO., OF NEW YORK, N. Y., A FIRM COMPOSED OF CHARLES F. KIMPTON, OF BROOKLYN, NEW YORK, HARRY HAUPT, OF ELMSFORD, NEW YORK, AND ELIZABETH H. HARBOTTLE, OF GARDEN CITY, LONG ISLAND, NEW YORK.

DESIGN FOR A PEN-RACK.

52,216.

Specification for Design. Patented July 23, 1918.

Application filed March 30, 1917. Serial No. 158,757. Term of patent 14 years.

To all whom it may concern:

Be it known that I, HARRY HAUPT, a citizen of the United States, residing at Elmsford, in the county of Westchester and State of New York, have invented a new, original, and ornamental Design for a Pen-Rack, of which the following is a specification, reference being had to the accompanying drawings, forming a part thereof, and in which—

Figure 1 is a perspective view;

Fig. 2 a side view; and
Fig. 3 an end view of a pen rack embodying my design.

I claim:

The ornamental design for a pen rack, as shown.

HARRY HAUPT.

Witnesses:

ARTHUR MARION,
CHAS. C. GILL.
